Attorneys

UNITED STATES PATENT OFFICE.

FRANK P. REYNOLDS, OF NORRISTOWN, PENNSYLVANIA, ASSIGNOR TO BALLARD KNITTING CO., OF NORRISTOWN, PENNSYLVANIA, A CORPORATION OF PENNSYLVANIA.

TAKE-UP MECHANISM FOR KNITTING-MACHINES.

1,393,039.

Specification of Letters Patent.

Patented Oct. 11, 1921.

Application filed May 17, 1920. Serial No. 382,006.

To all whom it may concern:

Be it known that I, FRANK P. REYNOLDS, a citizen of the United States, and resident of Norristown, Pennsylvania, have invented 5 certain new and useful Improvements in Take-Up Mechanisms for Knitting-Machines, of which the following is a specification.

My invention relates to take-up mechanism for knitting machines of the type disclosed in Letters Patent of the United States granted to G. L. Ballard #940,656, November 23, 1909, and one object of the invention is to simplify the construction and render 15 the action of the device certain and efficient under all conditions of use.

The invention is shown in the accompanying drawings in which:

Figure 1 is a side view of a take-up mechanism embodying the invention.

Fig. 2 is a detail view with parts in section.

Fig. 3 is a detail plan view of the lower clutch member and portions of the upper 25 clutch member.

Fig. 4 is a side view of the clutch members.

Fig. 5 is a perspective view of the lower clutch member.

Fig. 6 is a perspective view of an operating lever.

Figs. 7 and 8 are diagrams of the two positions of the clutch members.

In the drawings 1, 2, are the take-up rolls 35 journaled in the frame 3 which is pivotally mounted at 4. The fabric passing down from the needles goes between these rolls as is well known. The roll 2 has a worm wheel 5 mounted thereon driven by a worm 6 40 through which extends the drive shaft 7. This shaft at its lower end has a gear 8 to mesh with a circular fixed rack, as in ordinary practice, by which the shaft 7 is driven. The worm is provided with a clutch 45 member 9 and the drive shaft 7 has fixed thereto the upper clutch member 10. This upper clutch member has depending taper pins 11 to coat with inclined shoulders 12' on the lower clutch member 9. The vertical 50 drive shaft 7 as a whole is capable of vertical movement in its bearings and it carries with it the upper clutch member to raise or lower it bodily in relation to the lower clutch member, the upper bearing for this

shaft is shown at 13 in the frame arm 14. 55 A lever 15 is pivoted at 16 to the outer end of the frame arm 14 and this lever extends over the upper end of the shaft 7 and is connected by a link 17 with the pivoted frame 3 which as before stated, carries the take-up 60 rolls. The lever 15 is connected with the shaft 7 so as to positively lift the same, together with the upper clutch member, when the lever 15 moves upwardly due to the frame 3 moving in an upward direction 65 when the take-up rollers tend to climb on the fabric owing to the increased tension of the fabric between the take-up rolls and the needles. The lever 15 as in ordinary practice may be pressed downwardly by a suitable 70 spring or a weight may be used for this purpose. The lifting connection between the lever 15 and the upper clutch member may assume different forms, but in the particular construction shown, I employ 75 a forked portion 18, cast integral with the lever which engages under the head 19 formed on the upper end of the shaft 7. It will thus be seen that when the lever 15 moves upwardly due to the take-up rolls 80 climbing on the fabric when the tension increases, the fork lifts against the head 19 of the shaft and thus the shaft 7 will be lifted and the upper clutch member 10 will be raised so that its taper pins 11 will be 85 withdrawn slightly from contact with the inclined shoulders 12' on the lower clutch member 9 and therefore the worm will momentarily be free from the driving shaft 7, and during this time the tension of the fabric will be restored to normal condition owing to the continuation of the knitting at the needles. When the tension is restored to 90 normal condition, the take-up rolls weighing on the fabric will move downwardly with the fabric and link 17 will draw down upon the lever 15 and thus the shaft 7 will be lowered and the upper clutch member will bring its pins 11 into driving contact again with the shoulders of the lower clutch member 95 and the rotation of the take-up rolls will ensue. 100

It will be noticed that a slight lift on the upper clutch member will withdraw the taper surface of the pin from contact with the inclined shoulder on the lower clutch member, but that the faces of these parts will remain opposite each other in the sense that in 105

- both their engaged and released positions they are cut by the same horizontal plane. A long bearing face will be afforded between the contacting parts of the clutch when the 5 taper pins are in engagement with the inclined shoulders. These parts in the normal operation of the device are never moved out of their opposing paths, the lifting movement of the upper clutch member merely 10 bringing the small diameter part of the taper pin, opposite the inclined lug or rather maintaining the incline of the taper pin in the same horizontal plane with the lug on the lower clutch member. The clutch members, presenting as they do, metal to metal contact parts are not subject to changes due to atmospheric conditions and will not be affected adversely by the presence of oil as 15 is the case with the fiber disks. The connection between the lever 15 and the clutch being a positive one adapted to positively lift the upper clutch member, lends itself to efficient and sensitive coöperation with a clutch having metal to metal contact means 20 furnished by the taper pins and the inclined faced lugs. The shaft is of ordinary construction throughout, no slotting is required and no pressure pin or spring enters into the 25 present construction.
- 30 It will be observed that the lower clutch member is in the general form of a frustum of a cone and that the inclined shoulders 12' are formed by cutting away the conical body. These shoulders incline downwardly and 35 outwardly and conform with the general inclination of the side face of the frusto-conical member and the taper pins. The shoulders are formed by the lateral edges of the projections 12 whose outer faces also are of 40 the same degree of outward and downward inclination with the general conical shape of the lower clutch member. The bearing contact of the taper pins takes place throughout the entire length of the shoulder 12', the engagement being uniform at all points thus 45 giving a long wearing contact.

The taper pins are formed separately from the main body of the upper clutch member and have reduced shanks which are held in 50 sockets or openings of said main body by a driving fit or otherwise.

It will be understood that the structure of the parts disclosed herein is illustrative of my invention and is not to be regarded 55 as limiting the invention, the scope of which is defined by the appended claims.

A comparison of the diagrams Figs. 7 and 8 will illustrate the action of the clutch in its two positions, one, Fig. 7 being its driving position and the other, Fig. 8, its released position. These diagrams represent the lower clutch member as cut through at a horizontal plane intermediate of its height, the same horizontal plane of cut being represented in each figure. The inclined pe-

ripheral face of the lower clutch member below the plane of cut is not shown, the views as above stated, being in the nature of diagrams.

In Fig. 7, the taper pin is in its lowest 70 position and the line of section upon which the view is taken passes through lower member 9 and the pin, at the same level, and consequently the pin is shown as bearing with its curved side face against the shoulder 12'.

In Fig. 8 the line of section of the parts being at the same level as in Fig. 7 the lower clutch member appears the same as in Fig. 7, but because the taper pin is slightly raised 80 in this view the line of section cuts this pin at a zone on the pin of smaller diameter than in Fig. 7, and the slight crack or space appears between its curved side face and the shoulder 12'. This same crack or space, it 85 will be obvious, occurs throughout the length of the taper pin, and thus momentarily, the taper pin is out of driving contact with the inclined shoulder 12' and hence the take-up rolls for the moment will cease their rotation until a course or courses of knitting are 90 delivered from the needles and the tension is relieved, allowing the taper pins to resume contact with the lower clutch member, as shown in Fig. 7, for again driving the take- 95 up mechanism.

As just indicated, the cessation of the driving function of the clutch may be of a duration until a course or courses of knitting are delivered from the needles. Therefore the 100 outer or radially disposed faces of the shoulders of the frusto-conical lower clutch member are inclined downwardly and outwardly in conformity with the general incline of the sides of this member for the purpose of 105 allowing the taper pin to cross the outer face of the shoulder when said taper pin is lifted far enough to permit this action to take place, and thus sufficient fabric will be knit off, while the take-up is at rest, to relieve the tension. In this lifting movement, however, the taper pin will remain in the same horizontal plane with the shoulder as above described, or in other words, the taper pin and the shoulder will be cut by the same 110 horizontal plane in all positions of these two parts relative to each other. When the fabric tension relaxes, the taper pin will again lower, engage a shoulder and resume 115 its driving function.

This case is substituted for that filed by me August 19th, 1919, Serial No. 318,450.

I claim as my invention:

1. In combination in a take-up for knitting machines, a pair of take-up rolls, a movable support therefor, a worm and worm wheel for driving the take-up rolls, a clutch member connected with the worm having an inclined shoulder, a drive shaft extending 125 up through the worm, a clutch member fixed 130

on the drive shaft to move vertically therewith, having a taper pin to coact with the inclined shoulder on the clutch member first mentioned, a lever connected with the movable support of the take-up rolls and operating to effect a positive lifting action on the upper clutch member to release the side face of the taper pin from the inclined shoulder when the support of the take-up 10 rolls moves upwardly, substantially as described.

2. In combination in a take-up mechanism for knitting machines, take-up rolls, a worm and worm wheel for driving the take-up 15 rolls, a drive shaft, and a clutch between said drive shaft and the worm, comprising a member driven by the shaft and having a taper projection depending therefrom and a complementary member on the worm to be 20 engaged by the inclined side of said taper projection, substantially as described.

3. In combination in a take-up mechanism for knitting machines, take-up rolls, a worm and worm wheel for driving the take-up 25 rolls, a drive shaft, and a clutch between said drive shaft and the worm, comprising a member driven by the shaft and having inclined surfaces and a complementary member on the worm to be engaged by the inclined surfaces, said complementary member having inclined shoulders, said surfaces and shoulders when separated to retard the 30 drive, remaining in the same horizontal plane, substantially as described.

35 4. In combination in a take-up mechanism for knitting machines, take-up rolls, a worm and worm wheel for driving the take-up rolls, a drive shaft and a clutch between the said drive shaft and the worm, comprising a 40 member driven by the shaft and having taper pins with their axis parallel with the shaft and a complementary member on the worm having shoulders inclining outward and downward in conformity with the inclined side of the taper pins, substantially as described.

50 5. In combination in a take-up for knitting machines, take-up rolls, a worm and worm wheel for driving the take-up rolls, a drive shaft and a clutch between the said drive shaft and the worm comprising a member driven by the shaft and having taper pins with their axis parallel with the shaft and a complementary member on the worm 55 consisting of a frusto-conical disk provided with relatively high and low parts furnishing shoulders inclining outward and down-

ward in conformity with the inclined side of the taper pins, substantially as described.

6. In combination in a take-up mechanism 60 for knitting machines, take-up rolls, a worm and worm wheel for driving the take-up rolls, a drive shaft, and a clutch between said drive shaft and worm, comprising a member driven by the shaft, and a member 65 fixed to the worm, said members having relative movement in the direction of their common axis, one of said members having a shoulder inclined to the line of relative movement of the members and the other 70 member having a complementary inclined face, said inclined shoulder and complementary face being cut by the same horizontal plane in both their released and driving relations. 75

7. In combination, in a take-up mechanism for knitting machines, take-up rolls, a worm or worm wheel for driving the take-up rolls, a drive shaft, and a clutch between said drive shaft and worm comprising a member driven 80 by the shaft and having taper pins depending therefrom at different points about the same, and a frusto-conical member on the worm having its conical face provided with high and low parts forming shoulders 85 complementary in inclination to the side faces of the taper pins and against which shoulders the taper pins bear in driving the said frusto-conical member, and means for raising and lowering the member carrying the 90 taper pins to release and set the drive, said taper pins and shoulders being cut by the same horizontal plane in both their released and driving relations.

8. In combination in a take-up mechanism 95 for knitting machines, take-up rolls, a worm or worm wheel for driving the take-up rolls, a drive shaft, and a clutch between said drive shaft and worm comprising a member driven by the shaft and having a taper pin depending therefrom, and a frusto-conical member 100 on the worm having its conical face provided with high and low parts forming shoulders complementary in inclination to the side faces of the taper pin and means for raising 105 and lowering the member carrying the taper pin, the outer inclined faces of the shoulders permitting the taper pin to pass across them when the drive is released, substantially as described. 110

In testimony whereof, I affix my signature.

FRANK P. REYNOLDS.
